CARPET SWEEPER

Fred W. Pullen, Grand Rapids, Mich., assignor
to Bissell Carpet Sweeper Co., Grand Rapids,
Mich.

Application July 18, 1929. Serial No. 379,109

4 Claims. (Cl. 175—264)

This invention relates to improvements in carpet sweepers.

The object of the invention is to provide a carpet sweeper of ordinary construction with effective means for discharging statical electricity developed by the friction of the machine in operation.

Objects pertaining to details will appear from the description to follow. A preferred embodiment of my invention is illustrated in the accompanying drawing, in which:

Fig. 1 is a diagrammatic side elevation view of a carpet sweeper embodying the features of my invention, the handle being shown in broken section.

Fig. 2 is an enlarged detail elevation view of the handle.

Fig. 3 is a detail cross sectional view through the handle above the socket, on a line corresponding to line 3—3 of Figs. 1 and 2.

I show my invention in connection with an ordinary Bissell carpet sweeper which is here shown conventionally. The parts will be identified by their numerals of reference which are 25 the same in all the views.

The carpet sweeper body comprises the case 1, the floor wheels 2, the brush 3 with the usual construction of spring means 4. 5 is the handle bail. 6 is the handle socket and 7 is the handle 30 which is made of wood with a light coating of shellac or varnish.

I provide on the side of the handle a heavy graphite pencil mark 8 which extends from the socket 6 substantially to the top of the handle, 35 connecting to the metal screw-threaded ferrule 71 which is adapted to the socket 6. The line is applied to the wood before the shellac or varnish is applied.

Statical electricity under certain atmospheric 40 conditions develops to such an extent in the operation of a carpet sweeper over a carpet that it causes lint or any light fuzzy material to adhere to the carpet sweeper body, often to the extent of very materially interfering with 45 the operation of the carpet sweeper. It is often a mystery to the user because on picking up the carpet sweeper to examine it, the electricity is discharged and there is nothing in evidence anywhere to show what was causing 50 the trouble.

By providing a heavy graphite mark along the

wood handle the electricity, as fast as it is developed from the friction, is discharged through the handle and hands and body of the user to the floor or dissipated to the atmosphere. Of course, if there is not an actual discharge 60 to the floor, the distribution of the static electricity over the larger surface of the person of the user decreases its action to such an extent that the sweeper can be operated without material hindrance. However, under such circumstances the entire charge of statical electricity is usually discharged as fast as it forms.

This invention is, of course, of no avail or advantage where metallic handles are made use of. But such metallic handles are expensive 70 and unless made of light tubes of very high grade metal, they are unduly heavy and do not serve the purpose of a carpet sweeper as well as an ordinary light wood handle. Electric suction sweepers are usually provided with metal handles. Where wood handles are used statical electricity develops and should be discharged.

This invention is available on wood handles or fiber handles which are non-conductors of electricity on all kinds of sweepers, hand or electric.

Having thus described my invention, what I claim as new and desire to secure by Letters Patent, is:

1. The combination of a carpet sweeper, a 85 wood handle therefor with a metallic bail connected to the carpet sweeper, and a graphite line along the said handle from top to bottom adapted in use to connect the metallic parts with the hand of the user. 90

2. The combination of a carpet sweeper, a wood handle therefor with a metallic bail connected to the carpet sweeper, a graphite line along the said handle from top to bottom adapted in use to connect the metallic parts with the hand of the user, and a coat of varnish embracing said line. 95

3. A carpet sweeper with a wood handle in a metal socket having a graphite surface connection from the top end of the handle to the socket. 100

4. A carpet sweeper with a wood handle in a metal socket having a graphite surface connection from the top end of the handle to the socket, the said graphite surface connection being coated with varnish. 105

FRED W. PULLEN.
